UTILITY TOOL KIT

Louis Strauss, New York, N. Y.

Application October 8, 1947, Serial No. 778,599

1 Claim. (Cl. 7—16)

1

This invention relates to combination tools.

An object of the invention is to provide a combination tool or tool kit including a plurality of individual tool elements secured together and usable individually as desired.

Another object of the invention is to provide a combination tool including a handle or frame upon which a plurality of tool elements are carried, the arrangement being such as to facilitate the use of any particular tool element when needed, means being provided for extending such tool element outwardly from the frame and for locking it releasably in extended position.

A further object of the invention is to provide a combination tool including at least one edged tool element in the form of a knife or the like, other of the tool elements being so arranged as to normally include the knife between them and being so extensive as to prevent any danger to the user from the knife.

Still another object of the invention is to provide a combination tool or tool kit which is simple in design, inexpensive to manufacture, and which is easily assembled or disassembled when needed.

Other objects and advantages of the invention will become apparent from the following description of a preferred embodiment thereof as illustrated in the accompanying drawings, and in which,

Fig. 1 is a front elevational view of my improved combination tool, with one of the tool elements, namely the hammer in extended position,

Fig. 2 is a partly broken out left end elevation of the device shown in Fig. 1, the handle or frame and some of the underlying tool elements being partly broken out to illustrate the construction, and

Fig. 3 is a sectional plan view taken on line 3—3 of Fig. 1.

For the casual user of tools, it has been found to be quite expensive to purchase and maintain a complete set of individual tools, such as a hammer, saw, screw driver, and the like, it being also necessary to purchase or construct a tool box to contain and safeguard such tools. The present invention provides a combination tool or tool kit including a number of tool elements carried in a single frame which also serves as a handle.

In order to understand clearly the nature of the invention, and the best means for carrying it out, reference may now be had to the drawings, in which like numerals denote similar parts throughout the several views.

As shown, the device includes a substantially U-shaped frame or handle generally shown at 10

and comprising a lateral bridge member 12 interconnecting two resilient legs 14 and 16 the inherent spring in which biases them toward each other. The lower ends 18 of the legs 14 and 16 are provided on their inner surfaces with substantially cylindrical recesses 20 to receive the opposite ends of a shaft 22, which is retained in said recesses under the influence of their resilient bias toward each other, the shaft also serving to maintain the relative spacing between said legs.

5 A number of tool elements, each provided with a cylindrical shank 24, are retained pivotally on the shaft 22 between the handle legs 14 and 16 by having the shaft extend through axially aligned lateral bores 26 formed in the lower end portions of the tool element shanks, as seen best in Figs. 1 and 3. There are various types of tool elements, such as the awl 28, the saw 30, the corkscrew 32, and the hammer 34. There are also the drill 36, the anchor jar opener 38, the edged knife 40, and the can opener 42.

10 Each of the cylindrical shanks 24 of the tool elements has on one side a longitudinal groove 44 formed therein, the curvature of the groove being also cylindrical to receive the cylindrical surface of the adjacent tool element shank. In this manner, when the shanks of the tool elements are mutually parallel and parallel with the legs 14 and 16 of the handle 10, the shanks are all 15 locked together in that relative position. To accomplish this, without forming a similar longitudinal groove in the legs 14 and 16, one of the tool element shanks, namely that shown at location 46 in Figs. 1 and 3, is also provided with an additional longitudinal groove 48 in its surface 20 adjacent to the handle leg 16, to lock with that handle leg.

25 It will be seen that when it is desired to extend one of the tool elements from the handle frame, such as for example, the hammer 34, it is only necessary to pull upon that element, which results in a camming action to push the surrounding shanks and handle legs slightly apart, permitting the disengagement of the locking grooves, 30 and allowing the shank of the hammer to be turned through an angle of 180 degrees to its extended position.

35 Upon reaching this position, the shank of the hammer once again engages with the adjacent groove of the drill shank and its locking groove receives the curved surface of the shank of the screw driver 50, and is thus locked in extended position, the locking bias being provided by the 40 spring legs 14 and 16 pressing toward each other.

45 The hammer is also retractable to the dotted

line position shown in Fig. 1, by reversing the process described. When in retracted position, it will be noted that the hammer head extends over the tips of the other tools, forming a protective guard for the hands of the user who is obliged to grasp the handle while employing the particular tool element which is then extended.

It will also be noted that the user is protected from being cut by the knife blade when in retracted position, due to the arrangement in which the knife blade is disposed between the relatively broad and flat anchor opener and can opener 38 and 42 respectively. Since the ends of the shaft 22 are entirely concealed inside the recesses in the handle legs 14 and 16, there is no danger of them catching upon the clothing or of injuring the hands.

It will also be noted that by spreading the handle legs apart, to disengage them from the shaft 22, any desired tool element may be removed from the handle for repair or replacement, without use of any supplementary tools whatever and without damaging the tool itself or the frame. With all the tool elements retracted into the handle, the combination tool or tool kit may be placed in a leather or other type of container and placed in the pocket or in the glove compartment of an automobile for immediate use when needed. This is quite handy for all uses contemplated.

Although I have described my invention in specific terms, it is to be understood that various changes may be made in size, shape, materials and arrangement without departing from the spirit and scope of the invention as claimed.

I claim:

A combination tool comprising a frame in-

cluding a bridging member interconnecting two resilient frame legs, said legs being resiliently biased toward each other, sockets of predetermined depth formed in said legs adjacent the free ends thereof and facing each other, a shaft extending laterally between said legs and removably engaged in said sockets, said shaft being longer than the normal unsprung distance between said legs and being maintained in position 10 within said sockets solely by the resilient actions of said legs, a plurality of tool elements carried on said shaft, said tool elements being swingable to extended positions outwardly from said frame, and to retracted positions inside said frame, the 15 shanks of said tool elements being cylindrical with at least one locking groove formed longitudinally in the surface of each tool element shank to receive the curved surface of the adjacent tool element shank or frame leg when mutually parallel, whereby said tool elements are lockable in said extended and retracted positions.
